Harrison P. Hood.

UNITED STATES PATENT OFFICE.

HARRISON P. HOOD, OF INDIANAPOLIS, INDIANA.

IMPROVEMENT IN WRENCHES.

Specification forming part of Letters Patent No. **146,254**, dated January 6, 1874; application filed June 18, 1873.

To all whom it may concern:

Be it known that I, HARRISON P. HOOD, of Indianapolis, county of Marion and State of Indiana, have invented a Railway-Wrench, of which the following is a specification:

The object of my invention is to provide a wrench for turning the nuts upon track-bolts used in the construction of railroads, which shall be more rapid, powerful, and convenient in its operation than those heretofore made or known; and consists, first, of an oscillating lever and a socket for embracing a nut, in connection with certain ratchets, pawls, and cog-wheels, so arranged that both the forward and backward oscillations of the lever cause the socket to rotate in the same direction, all suitably mounted in a frame and adapted to be used upon a rail or rails for turning nuts upon track-bolts; second, in so constructing the ratchet and cog wheels, and arranging them in relation to the lever and the socket for embracing the nut, that the movement of the lever in one direction will impart to the nut a slow, powerful movement, and the movement of the lever in the opposite direction will impart to the nut a more rapid but less powerful movement in the same direction; third, in the construction and arrangement of the socket for embracing the nut in a case so constructed and arranged in relation to the other parts of the machine that the socket may be adjusted, and applied to, and removed from the nut while the other parts of the machine are at rest upon the rail; fourth, in so constructing and adapting to a rail a wrench for turning nuts upon track-bolts that it may be easily and conveniently propelled along and upon the rails from bolt to bolt, and from joint to joint, and stopped, and thereby made secure to the rail while turning the nut; fifth, in a clamping device for fastening the wrench to the rail.

Figure 1, in the accompanying drawings, is a side elevation of my invention attached to the rails R, which are connected by the splice-bars S, which are held in place by the nuts n n n. Fig. 2 is a plan. Fig. 3 is a partial rear elevation, showing the clamping device. Fig. 4 is the socket-wheel, shown in detail, A being a front elevation, and a a side elevation. Fig. 5 is a front elevation of the case in which

the socket A has its bearings, and also a partial view of one of the wheels which conveys the motion of the oscillating lever to the socket.

The details of construction are as follows: The socket A, Figs. 1 and 4, is provided with bearings x, which have their seats in case B, Figs. 1, and 2, and 5. The cog-wheel C, Figs. 1 and 5, also has its bearings in the case B, and engages with the socket-wheel A. The cog-wheel C, with the case B, carrying the socket-wheel A, is placed upon the shaft b, Fig. 2, which has its bearings in the frame K. The construction at this point is such that the case B, with its contents, may be moved laterally in relation to the frame K and other parts, for the purpose of placing it in position on the nut and removing it therefrom while the other parts of the machine are at rest upon the rail, and it is also free to move in a rotary manner around or partially around the shaft b, for the purpose of adjusting the socket vertically to the varying position of the nuts on different rails, and also to admit of swinging the case and socket into the space P, Fig. 2, when not in use. A cog-wheel, E, having upon a portion of its periphery a double set of ratchet-teeth, facing in opposite directions, 1 2, Fig. 2, is so placed on a shaft in the frame K that its cogs will engage with those of the wheel C when the socket-wheel A is in position for turning the nut. Another wheel, F, similar to the wheel E, but differing therefrom in this, that the portion of its periphery having cogs is smaller in diameter, is placed opposite it, and between them is placed the lever D, Figs. 1 and 2, bearing upon its sides the double pawls d and e, which engage alternately with the wheels E and F as the lever D is oscillated on its fulcrum, which is concentric with the wheels E and F. A shaft, h, is provided, on which is fastened the cog-wheel I, which engages with the wheel E, and the cog-wheel H, which engages with the wheel F through the intermediate wheel G. A crank, m, is attached to the shaft h, by means of which the nut may be turned without the use of the lever D when but little power is required. The wheels J, having flanges which project on each side of the rail R, are placed on suitable shafts in the frame, and serve to support and keep the ma-

chine in position on the rail, and also provide a means for moving it easily along from joint to joint and from bolt to bolt.

It is obvious that wheels without flanges might be used, and the flanges or guides attached to some other part of the machine, as the frame; or the wheels might be dispensed with altogether, and the machine, held in position and guided by the flanges, or their equivalent, might be slid along upon the rail; but I prefer the method here shown.

A clamp for fastening the machine firmly to the rail while turning the nuts is attached to the rear end of the frame K, or in any other suitable position; and consists of the jointed levers L, Figs. 1 and 5, connected at their longer ends by the notched bar c, to which the cam-lever f is attached. A spring, 3, Fig. 2, serves, by contact with the head of the track-bolt, to keep the bolt from being pressed out, when the socket is applied to the nut, and also to indicate, by its position on the head of the bolt, when the machine is in proper position for stopping it in its passage along the rail.

The manner of operation is as follows: The wrench or machine having been placed upon a line of rails, it is run forward upon the rails until the spring 3, Fig. 2, comes in contact with the head of a track-bolt. The long arms of the jointed levers L are then brought toward each other, which closes the short arms or jaws upon the rail. The notched connecting-bar c, Fig. 3, is then slid along through the slots, in which it rests until the cam-lever f, presenting the thin side of its cam, is brought against one long arm, and one of the notches drops over a projection on the other. The cam-lever is now pressed down and the jaws are drawn forcibly together on the rail, thus fastening the machine securely to the rail. The case B, with its socket-wheel A, is now swung down out of the opening P, where it had rested, and is moved laterally until the socket embraces the nut, which is upon the bolt, and the cog-wheel C engages the wheel E, where it is held by the cap o dropping down over the end of the shaft b. The lever D now being moved in one direction, the pawl e engages one of the ratchets in the wheel F, carrying it with the lever, and thus giving, with great power, through the connecting-wheels and socket A, a slow rotary motion to the nut. In moving the lever D in the opposite direction, the pawl d engages one of the ratchets in the wheel E, carrying it with the lever, and thus revolving the nut in the same direction as before, but with increased speed and less power, thus giving an alternate slow and fast motion to the nut, and enabling the operator to turn the nut on or off quickly, and

also giving him power to force the nut over rough places on the bolt, and to set it firmly to its bearing. This is accomplished in the following manner: Whenever a rough or uneven place in the threads, either of bolt or nut, is encountered in turning the nut off or on the bolt, or when the nut comes to its bearing, the rapid motion may be dispensed with at will by raising the pawl d out of connection with the ratchet on E, and using as long as may be necessary the slow powerful movement.

When two nuts are used on one bolt, as is most frequently the case, after the first nut has been turned onto the bolt so far that the end of the bolt projects slightly through the nut, the second nut is introduced into the socket and turned on at the same time with the first. When the first nut comes to its bearing, it becomes necessary to turn the second nut without turning the first, in order to set it firmly against the first. This is accomplished by moving the socket and its case laterally away from the first nut until the socket will revolve clear of it. It is retained in this position by the cap o falling into a groove in the shaft b, and the second nut is then revolved, by the same means as before, until it sits firmly against the first. By reversing the position of the pawls d and e—that is, by turning them over, the other side up—they will engage with the sets of ratchet-teeth on the wheels E and F which were before idle, and the same motions of the lever which before turned the nut on will now turn it off the bolt.

What I claim as my invention is—

1. The laterally and vertically adjustable case B, provided with the cog-wheel A, having a nut-orifice, and the cog-wheel C, substantially as and for the purposes set forth.

2. The combination of the cog-wheels E F, both having a double row of ratchet-teeth, facing in opposite directions, and mounted upon a shaft, with the lever D, reversible double pawls d e, and the wheels C A in the suspended case B, all substantially as and for the purposes set forth.

3. The combination of the frame K and the front and rear flanged wheels J j, or their equivalents, supporting a mechanism for turning nuts on a railroad-rail, as set forth.

4. The combination, with the frame K, of the pivoted cross-levers L L, notched connecting-bar c, and cam-lever f, for holding the movable frame and its nut-turning mechanism rigidly to the rails, substantially as set forth.
